UNITED STATES PATENT OFFICE.

LESTER F. ROSENBAUM, OF KALAMAZOO, MICHIGAN, ASSIGNOR TO SAM ROSENBAUM & SONS COMPANY, OF KALAMAZOO, MICHIGAN.

KNICKERBOCKERS.

Application filed August 17, 1923. Serial No. 657,887.

This invention relates to improvements in knickerbockers.

The main object of this invention is to provide a knickerbocker having leg fents in which the band may be adjusted to the leg of the wearer, and quickly released or engaged without the necessity of readjustment.

A further object is to provide a garment having these advantages which is very economical in material and manufacture, the hand work and special machine work being minimized.

Objects pertaining to details and economies of my invention will definitely appear from the detailed description to follow.

I accomplish the objects of my invention by the devices and means described in the following specification. The invention is clearly defined and pointed out in the claim.

20 A garment embodying the features of my invention is clearly illustrated in the accompanying drawing forming a part of this application, in which:

25 Fig. I is a side view of a garment embodying the features of my invention.

Fig. II is an enlarged fragmentary view with the fent open, the closure strap being removed.

30 Fig. III is a plan view of the fent closure strap.

Fig. IV is a detail section on a line corresponding to line 4—4 of Fig. II, the thickness of the fabrics being greatly exaggerated for convenience in illustration.

35 In the drawing similar reference characters indicate similar parts in all of the views.

Referring to the drawing, the leg 1 is provided with a fent 2 at the outer side thereof, the fent being formed at the lower 40 end of the side seam 3 and formed with overlapping edges 5 and 6. The band 7 is of uniform width throughout and is secured throughout its top and bottom edges by the rows of stitching 8. This may be done on a 45 double needle machine. The ends of the band terminate at the edges of the fent.

Inner facings 9 are provided for the fent edges, these facings being secured by welt seams as shown in Fig. IV. This provides an effective finish for the edges of the fent 50 and one which does not greatly increase the thickness as thin materials may be effectively used for the facings. I have not attempted to illustrate in the drawings the difference in thickness of material.

55 The adjusting strap 10 is formed independently of the band and is adjustably secured thereto by means of the buckle 11. The strap is provided with a button 12 at one end which may be engaged with the 60 button-hole 13 formed adjacent the edge of the overlapping portion of the fent. This permits adjustment of the band to the needs of the particular wearer and enables the quick opening and closing of the fent by 65 means of the button.

This is also of great advantage from a manufacturing standpoint as it reduces hand work to a minimum, the straight band permitting the use of a double needle machine 70 in the attaching of the band, and it also results in a considerable saving of the material.

Having thus described my invention what I claim as new and desire to secure 75 by Letters Patent is:

A garment having a leg provided with a fent at the bottom thereof having overlapping edges, a band of uniform width stitched throughout its length at its top and 80 bottom edges terminating at the edges of said fent, said band having a button-hole at its overlapping end, an adjusting strap provided with a button at one end to coact with said button-hole, and a buckle disposed in 85 spaced relation to the underlapping end of said band for adjustably connecting said strap to said band.

In witness whereof I have hereunto set my hand.

LESTER F. ROSENBAUM.
